(57) **CLAIM**

The ornamental design for articles of footwear, as shown and described.

DESCRIPTION

FIG. 1 is a right-front perspective view of one article of a pair of articles of footwear, showing my new design;

FIG. 2 is a left-front perspective view thereof;

FIG. 3 is a right-rear perspective view thereof;

FIG. 4 is a left-rear perspective view thereof;

FIG. 5 is a front view thereof;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.

The drawings show the design for an article of footwear suitable to be worn on a right foot. The design for an article of footwear suitable for being worn on the left foot would be a mirror image.
